MACHINE FOR THE MANUFACTURE OF
CIGAR BUNCHES OR THE LIKEKarl Erik Granstedt, Stockholm, Sweden, assignor

6 Claims. (Cl. 131—33)

This invention relates to machines for the manufacture of cigar bunches or the like. In the operation of such a machine of a well known type the operator located in front of the rolling table places individual sheets of material for forming the binders, each consisting of half a tobacco leaf, for instance, on the rolling apron, which winds the tobacco filler into same. The bunch thus produced is delivered by the apron at the front end of the rolling table and is picked up thereby the operator and placed into a pressing mould or mechanism. This use of half leaves causes considerable waste of tobacco, since generally a considerable part of each half leaf is not required for the binding of the tobacco filler. Furthermore, the sizes of such tobacco leaf halves forming binders are variable, so that the size of the finished cigars might differ. Therefore, it has been found advisable to cut out of the tobacco leaf the part only that is necessary for the producing of the bunch binder, and to utilize the waste parts for other purpose. In other machines hitherto known this has been accomplished by cutting the binder on a cutting die, from which the binder is automatically transferred to the bunch rolling table. By the use of such a cutting die and transfer the capacity of the machine has been increased since the application of the tobacco leaf on the cutting die and the cutting and removal of the binder from the die can take place simultaneously with the winding of a tobacco filler into a binder previously delivered to the rolling table. Such improvements have been accompanied, however, by certain drawbacks that do not affect the simple machine to be served manually as described previously. Thus the automatically operating machine is expensive, and it cannot easily be served by a single operator, unless the finished bunches are transferred automatically from the bunch rolling table to a suitable position convenient to the operator. Such an automatic transfer would, however, make the machine still more complicated and expensive, partly on account of the necessity of means for the automatic transfer, partly because the bunch thus transferred would have to be pasted so as to prevent the binder from getting loose of the filler. Moreover, such pasting might deteriorate the product inasmuch as the adhesive (if not of a very high quality) may impair the taste of the cigar when ignited.

It is a main object of my present invention to make provision for utilizing the advantages mentioned above and avoiding the drawback, thus

providing a machine in the operation of which tobacco is saved, the output of which is high and which can easily be served by a single operator. Machines of the simple and inexpensive type previously mentioned can easily be rebuilt for that purpose. It will not be necessary to make radical changes of the constructions and arrangements of such machines already existing in plants for the manufacture of cigars. Thus, in plants in which the bunch machines are associated with juxtaposed bunch compressing and wrapping machines no change of the relative positions of said machines will be necessary, which is very important, particularly where such change might be impossible because the space is limited.

To the accomplishment of the foregoing and such other objects as may hereinafter appear, my invention resides in the construction and novel combination of parts fully described hereinafter, illustrated in the accompanying drawings, and pointed out in the claims appended hereto, it being understood that various changes in the form, proportion and arrangement of the various parts within the scope of the claims, may be resorted to without departing from the spirit of my invention.

In the drawings:

Fig. 1 is a plan view of an embodiment of the machine, several parts thereof being broken away to more clearly disclose the invention;

Fig. 2 is an elevational sectional view taken on the line II—II of Fig. 1, with the binder cutting means in its advanced position;

Fig. 3 is a longitudinal sectional view, taken on the line III—III of Fig. 2;

Fig. 4 is a side elevational view, partly in section, taken on the line IV—IV of Fig. 2;

Fig. 5 is a longitudinal sectional view on the line V—V of Fig. 2; and

Fig. 6 is a vertical cross sectional view on the line VI—VI of Fig. 1.

Referring to the drawings, the cigar bunch machine has a bunch rolling table 1 upon which is placed a bunch rolling apron 2. In front of the table 1, relatively near same, is positioned a die 3 for cutting out binders of tobacco leaves taken by the operator at 4 from a supply on the table 5 and placed upon the cutting die. To cut the binder, two cutting rollers 6 and 7 are movable across the cutting die 3, pressing upon its cutting edge 8 which is positioned obliquely relative to the direction of movement of the cutting rollers. The cutting rollers 6 and 7 are rotatably mounted each on an arm 9 and 10,

respectively, and are rigidly connected each to a supporting roller 40 which is adapted to roll upon a bar 11 arranged slightly below the level of the cutting edge 8. The arms 9 and 10 are by means of tension springs 41 connected to an arm 12 which is pivoted to the arm 9 and provided with a rotatably journaled roller 13 which by the spring 41 is pressed against the underside of the bar 11. The arms 9 and 10 are both pivoted to a lever arm 15 which is pivotally mounted on a stationary shaft 14. The lever arm 15 is by means of links and arms driven by a cam disk 17 which is secured to a rotatably journaled driving shaft 16. Thereby, the cutting rollers 6 and 7 are moved back and forth across the cutting edge 8.

The cut binder is transferred from the cutting die 3 to the bunch rolling table 1 by a binder carrier 18. The table 1 is perforated in its upper surface and interiorly connected to a suction conduit 48 which is also connected to the cutting die 3 and the binder carrier 18. As the suction surface of the binder carrier 18 is flat the surface 19 of the bunch rolling table upon which the binder is placed should also be flat. The flat surface 19 may, however, not be too wide, for then the bunching roller 20 cannot satisfactorily enclose the bunch within the rolling apron 2, when it is moved across said surface 19 at some distance above same. Therefore, the extent of the surface 19 in the longitudinal direction of the bunch rolling table 1 is somewhat less than that of the binder, i. e. of the cutting edge 8. Therefore, the flat suction surface of the binder carrier 18 at its corners 21 does not place the binder in tight engagement with the rolling apron 2. However, this does not cause any inconvenience since the apron is perforated so that it can transmit the suction effect from the perforated rolling table 1 when valve 31 is open and suck to the apron the ends of the binder projecting beyond the flat surface 19 when the suction in carrier 18 is destroyed by closing of valve 32 (Fig. 3). The tobacco filler placed into the pocket 22 of the apron 2 is in usual manner wound up by the bunch roller 20 and apron into the binder, and the wound bunch A is by the apron introduced into a yieldable holder 23 at the front end of the rolling table 1.

The binder carrier 18 is pivotally journaled on a hollow arm 24 which is secured to a rock shaft 26 which is rotatably journaled in a bracket 25. The shaft 26 is hollow and perforated so as to communicate with the suction conduit 48. The shaft 26 is driven by an arm 41, a link 42, a double-armed lever 43, a link 44 and a cam disc 45 which is secured to the shaft 16. In order to adjust the binder carrier 18 to direct its suction surface parallel to the sloping surface 19 of the table 1, when the carrier is moved from the horizontal cutting die to the surface 19, a link 27 is pivotally connected to an arm 28 fixed to the bracket 25 and to another arm 29 that is slightly shorter than the arm 28 and is secured to the binder carrier 18. The suction effect in the cutting die 3, the rolling table 1 and the binder carrier 18 are as usual created periodically by means of automatically operated valves 30, 31 and 32, respectively. The bunch roller 20 is rotatably journaled in the bifurcated end of a long lever arm 33 which is pivotally journaled on a shaft 24 that is positioned at the bottom of the machine frame in a plane extending transversely

to the centre portion of the surface 19 and parallel with the shaft 26. The lever arm 33 is swung back and forth by a link 35 that is actuated by a cam disc 36 secured to the shaft 16. The shafts 26 and 34 are parallel.

The distance of the cutting die 3 from the front end of the bunch rolling table 1 is not greater than that required to enable the cutting rollers 6 and 7 to move past the cutting edge 8 to a position immediately in front of the bunch holder 23. After the cutting operation the rollers 6 and 7 return to their initial position (see Fig. 5) below the supply table 5. Therefore, the operator positioned at 4 can, over the cutting die 3, easily reach the bunch A in the holder 23, remove it from said holder and transfer it manually into a mould press of wood or a revolving mould drum of a cigar machine (not shown) mounted in the proximity of the cigar bunch machine. During such transfer the operator can hold the binder fast about the filler, so that no pasting is required to adhere the binder to the filler. A tobacco leaf can be picked up by the operator from the table 5 and placed onto the cutting die 3 simultaneously as a tobacco filler is wound up into the binder previously cut out. Thus, as distinguished from known bunch machines of the main type to which this invention relates, the operator needs not be inactive and wait for the end of the winding process and the return of the bunch roller 20 before applying the binder manually. The operator usually occupied with the application of tobacco leaves on the cutting die can easily reach the finished bunch, take it out of the holder 23 and put it into a press mould since the bunch is easily accessible over the cutting die. As no means are required for conveying the bunch to the pressing mould there is no risk that the binder will get loose of the filler when the bunch is transferred to the press mould. Therefore, no supply of paste to the binder is required. In order still more to facilitate the attendance to the machine the cutting die 3 may be movable up and down, so that it is elevated from a position of rest (shown in dash and dot lines in Fig. 4) into a position, substantially at a level with the table 5, in which position a tobacco leaf is placed onto the cutting die. Thereafter, the die is moved down into the cutting position shown in dash and dot lines in Fig. 4, and the cutting rollers 6 and 7 are put into operation simultaneously as a winding operation takes place. For that purpose, the cutting die 3 together with its cutting edge 8 are mounted on a rod 37 which is movable up and down in the machine frame and driven by a lever arm 38 which is pivotally journaled on the shaft 14 and actuated by a cam disc 39 secured to the shaft 16.

I claim:

1. In a machine for the manufacture of cigar bunches or the like, a bunch rolling table having a delivery front end, a table for a supply of tobacco leaves positioned in front of said rolling table, a binder cutting die located between and in the proximity of said delivery end of said rolling table and an oppositely disposed front end of said supply table, a binder cutting roller, means for positively reciprocating said cutting roller over said die between an initial position of rest in the proximity of said end of said supply table and a point in the proximity of said delivery end of said rolling table, a bunch rolling apron on said bunch rolling table,

and means for transferring binders from said die to said rolling apron.

2. In a machine for the manufacture of cigar bunches or the like, a bunch rolling table having a delivery front end, a table for a supply of tobacco leaves positioned in front of said rolling table, a binder cutting die located at said supply table in the proximity of said delivery end of said rolling table, a binder cutting roller, means for reciprocating said cutting roller over said die between an initial position of rest below said supply table and a point in the proximity of said delivery end of said rolling table, and means for transferring binders from said die to said rolling table.

3. In a machine for the manufacture of cigar bunches or the like, a bunch rolling table having a delivery front end, a table for a supply of tobacco leaves positioned in front of said rolling table, a binder cutting die located at said supply table in the proximity of said delivery end of said rolling table, a binder cutting roller, means for periodically moving said cutting die in front of said supply table between an upper leaf applying position and a lower binder cutting position, means for moving said cutting roller from an initial position of rest below said supply table over said die in said cutting position, and means for transferring binders from said die to said rolling table.

4. In a machine for the manufacture of cigar bunches or the like, a bunch rolling table having a delivery front end, a table for a supply of tobacco leaves positioned in front of said rolling table, a binder cutting die located at said supply table in the proximity of said delivery end of said rolling table, a binder cutting roller, means for periodically moving said cutting die between a leaf applying position in front of said end of

said cutting table and a cutting position at a level below said supply table, means for moving said cutting roller from an initial position of rest below said supply table over said die in said cutting position, and means for transferring binders from said die to said rolling table after said die has been elevated into its upper position in front of said supply table.

5. In a machine for the manufacture of cigar bunches or the like, a bunch rolling table having a delivery front end, a table for a supply of tobacco leaves positioned in front of said rolling table, a binder cutting die located at said supply table in the proximity of said delivery end of said rolling table, a binder cutting roller, means for reciprocating said cutting roller over said die between a position below said supply table and a position in the proximity of said delivery end of said rolling table, and means for transferring binders from said die to said rolling table.

6. In a machine for the manufacture of cigar bunches or the like, a bunch rolling table having a delivery front end, a table for a supply of tobacco leaves positioned in front of said rolling table, a binder cutting die located at said supply table in the proximity of said delivery end of said rolling table, a binder cutting roller, means for periodically moving said cutting die in front of said supply table between an upper leaf applying position and a lower binder cutting position, means for moving said cutting roller over said die in said cutting position between a position below said supply table and a position in the proximity of said delivery end of said rolling table, and means for transferring binders from said die to said rolling table.

KARL ERIK GRANSTEDT.
